FEED MECHANISM FOR SEWING MACHINES

Frank A. Kucera, Chicago, Ill., assignor to Union
Special Machine Company, Chicago, Ill., a cor-
poration of Illinois

Application September 11, 1936, Serial No. 100,259

14 Claims. (Cl. 112—214)

This invention relates to feeding mechanism for sewing machines; and it has reference more particularly to feeding mechanism for that type of sewing machine wherein a presser bar is confined to vertical movement in a needle arm which overhangs a work support whereon the fabric being seamed is advanced to the stitch-forming instrumentalities of the machine.

My invention is directed toward the provision of a simple and reliable feed mechanism wherein a feed element in the form of a wheel, and an associated presser foot are supported at the lower end of the presser bar in adjacent relation in the line of feeding in such manner as to be capable of yielding independently as irregularities in the fabric pass beneath them on the work support.

In connection with feed mechanism characterized as above, I aim to provide flexible actuating means whereby the feed roller is positively and uniformly rotated intermittently notwithstanding its up and down movements in compensating for variations in the fabric thickness.

Another object of my invention is to secure the foregoing advantages in a feeding mechanism which can be used in an auxiliary capacity with the usual four motion feed dog of a sewing machine of the kind referred to, with the dog cooperating directly with the presser foot of the auxiliary mechanism, and the roller of said mechanism disposed rearward beyond the presser foot and assisting the feed dog in progressing the fabric relative to the stitch forming instrumentalities of the machine.

Other objects and attendant advantages will appear from the detailed description of the attached drawings, wherein Fig. I shows the rear elevation of a sewing machine conveniently embodying the feed mechanism of my invention, portions of the frame of the machine being broken out to expose important details which would otherwise be hidden.

Fig. II shows the elevation of the forward end of the machine with portions of the frame removed and others broken out, likewise to expose important details.

Fig. III is a fragmentary detail section view drawn to a larger scale and taken as indicated by the arrows III—III in Fig. I.

Fig. IV is a fragmentary detail plan sectional view taken as indicated by the arrows IV—IV in Fig. III; and

Fig. V is a fragmentary detail view taken as indicated by the arrows V—V in Fig. III.

The frame of the sewing machine herein illustrated has a hollow base 1, providing a horizontal

work support 1a which is overhung by a hollow arm 2 extending longitudinal of the machine from a hollow standard 3 at one end of said base. Guided for axial reciprocation in a head 4 at the free end of the overhanging arm 2 above a throat plate 5 secured to the work support 1a is a vertical bar 6 (see Fig. II) carrying a pair of sewing needles 7 at its lower end. The needle bar 6 is actuated, through suitable interposed connections (not shown) within the head 4, the arm 2 and the standard 3, by a crank 8 on a longitudinal drive shaft 9 suitably journaled within the hollow base 1 of the machine frame. Disposed rearwardly of the needle bar 6 (as considered with regard to the direction of feeding which is indicated by the arrows in Figs. II and III), and confined to axial movement in the head 4, is the presser bar 10 of the machine. By means of a flat adjustable leaf spring 11 supported on the top of the arm 2 with its free end bearing on a stirrup 12 engaged over the upper end of the presser bar 10, said bar is yieldingly urged downwardly toward the work support 1a.

The feeding mechanism with which the present invention is more especially concerned, comprises a toothed wheel 13 which is journaled within a yoke 14 at the bottom of the presser bar 10 for free rotation about a transverse axis pin 15. As shown, the yoke 14 is rigidly secured to the feed bar 10 by a pair of set screws 16, and said bar held against rotation through engagement of the downward and outward projection 17 of a collar 18 thereon with a vertical slot 19 at one side of said head, see Figs. I and II. As shown in Figs. IV and V, the feed wheel 13 has hollows 20, 21 at opposite sides thereof for accommodating the parts of a roller clutch means whereby it is intermittently rotated to progress the fabric F (Fig. III) along the work support 1a of the machine. The clutch means just referred to includes a notched cam disk 22 which is secured by screws 23 to one side of the yoke 14 and wherewith cooperate a pair of spring urged rollers 25 within the hollow 20. Occupying the hollow 21 at the other side of the feed wheel 13 is a reversely notched cam disk 26 wherewith cooperate a pair of spring urged rollers 27, said disk 26 being secured by screws 28 to the fulcrum boss 29 of an upwardly-projecting, laterally-offset actuating arm 30 which engages the pin 15 in an interval between the wheel at the corresponding side and the contiguous side of the yoke. At its upper end, the actuating arm 30 is coupled, by means of a link 31, with the lower end of a pendant arm 32 affixed to the forward end of a rock shaft 33.

which extends longitudinally of the rear side of the needle arm 2, as shown in Figs. I and II, and which is journalled in suitably spaced bearings 34, 35 secured by screws 36, 37 to said needle arm. 5 To the opposite end of the rock shaft 33 is affixed an arm 38 which extends inwardly through an opening 39 in the corresponding side of the standard 3 and which is connected by means of a vertical eccentric rod 40 within said standard, with a 10 crank 41 on the drive shaft 9 immediately adjacent the crank 8 hereinbefore mentioned. As the actuating arm 30 moves clockwise in Fig. III, the rollers 27 are wedged between the sloping edges of the notches in the cam disk 26 and the 15 inner periphery of the wheel 13 within the hollow 21, and said wheel thereby given a rotary shift to advance the fabric F. On the other hand, when the actuating arm 30 is swung in the opposite direction, easement of the rollers 27 takes 20 place, while the feed wheel 13 is held against rotation through wedging action of the other set of rollers 25 between the inclined edges of the notches in the disk 22 and the inner periphery of said feed wheel within the hollow 20. In order 25 that the amount of movement thus imparted to the wheel 13 may be regulated, the pendant arm 32 on the rock shaft 33 is constructed with two parts 32a and 32b, the first of which has a longitudinal slot 42 and the other of which carries a 30 clamp screw 43 which is adjustable along said slot. For the protection of the operator of the machine, the feed wheel 13 is covered by a guard 44 suitably attached to the top of the yoke 14 as shown.

Associated with the feed wheel 13 and located 35 ahead of it in the direction of feeding (indicated by the arrows in Figs. II and IV) is a presser foot 45 which is formed with a flat portion 45a to bear upon the top of the fabric F and with an upwardly inclined frontal deflecting portion 45b, 40 said presser foot having elongated apertures 46 to clear the length of its horizontal portion 45a, the presser foot 45 is provided at opposite sides with integral upstanding ears 47 which are pivotally 45 connected, by means of screws 48, to the forward extremities of an H-shaped link member 49 whereof the rear extremities are fulcrumed by screws 50 to the opposite sides of the yoke 14, see Figs. III and IV. Finger springs 51 with 50 coiled portions 52 surrounding anchorage screws 53 at opposite sides of the yoke 14 bear upon the forward extremities of the link member 49, with their ends engaging grooves 54 in said extremities so as to be thereby held against lateral displacement. By virtue of the construction just 55 described, the presser foot 45 is accorded the capacity to move bodily up and down independently of the feed wheel 13 in facilitating passage of fabric irregularities beneath it, as well as to 60 swing or rock independently about its pivotal connections 48 with the link member, which latter movement is yieldingly resisted by a finger spring 55 (Figs. III and IV) which is secured by a screw 56 to one side of the link member 49, and which has its free end retroverted as at 65 57 and bearing on the flat top of one of the ears 47.

For the purpose of limiting the downward 70 movement of the presser foot when the presser bar 10 is elevated to lift the feed wheel 13 clear of the work support 1a, there is provided a vertical keeper link 58 whereof the lower end is pivotally connected to a central lug 59 on the transverse bar 49a (Fig. IV) of the link member 49, and whereof the upper end is longitudi-

nally slotted as at 60 in Fig. III, for passage of the shank of a headed screw stud projection 61 on the collar portion 14a of the yoke 14. As shown the slot 60 in the link 58 is of such length as to normally permit the independent up and down and rocking movement of the presser foot 45; but as the presser bar 10 is raised as aforesaid to lift the feed wheel clear of the work support 1a, the upper edge of said slot will engage the stud projection 61 and thereby limit the 10 downward movement of the link member. Thus, as elevation of the presser bar continues, the presser foot 45 will in turn be lifted clear of the work support 1a, and, conversely, will be the first to contact with said work support when the 15 presser bar 10 is subsequently lowered.

The feed mechanism of my invention may be used alone; or it may be employed in an auxiliary capacity to the usual four motion feed dog 62 (Figs. II and IV) of the sewing machine, 20 when the character of the fabric makes this desirable. It is to be particularly noted that the feed dog 62 coacts through openings 63 in the throat plate 5 directly with presser foot 45 only; and moreover, that feed wheel 13 engages that 25 portion of the fabric F on the throat plate 5 beyond said presser foot and rearward of the latter in the line of feed. The actuating mechanism for the feed dog 62 is generally designated by the numeral 64 in Fig. II, and lies beneath the work support 1a, and may be of a type which derives its movements from the drive shaft 9. It is, of course, to be understood that in practice, the parts are so adjusted that the 30 rotary shifts of the feed wheel 13 are synchronized and made to correspond exactly in extent with the active or feed movements of the feed dog 62 to prevent either stretching or crowding of the fabric between the two.

Having thus described my invention, I claim:

1. Feeding mechanism for sewing machines comprising a presser bar confined to axial movement above the work support of the sewing machine; a feed wheel rotatable about an axis carried by the presser bar for vertical movement directly with said bar; means for rotating the wheel to progress fabric along the work support relative to the stitch-forming instrumentalities of the machine; a horizontal link member pivoted for up and down movement on the presser bar; a presser foot attached to the link with capacity for independent pivotal movement; and means for yieldingly maintaining the presser foot in engagement with the fabric. 40

2. Feeding mechanism for sewing machines comprising a presser bar confined to axial movement above the work support of the sewing machine; a feed wheel carried by the presser bar; means for rotating the wheel to progress fabric along the work support relative to the stitch-forming instrumentalities of the machine; a horizontal link member pivoted for up and down movement on the presser bar; a presser foot attached to the link with capacity for independent pivotal movement; means for yieldingly maintaining the presser foot in engagement with the fabric; and means for yieldingly resisting the independent pivotal movement of said presser foot. 55

3. Feeding mechanism for sewing machines comprising a presser bar confined to axial movement above the work support of the sewing machine; a feed wheel rotatable about an axis fixed on the presser bar rearward of the needle of the machine in the line of feeding for vertical move- 70 75

ment directly with said bar; and an associated presser foot ahead of the feed wheel in the line of feeding and pivoted to the presser bar with capacity for movement independently of said bar and said wheel to compensate for irregularities in the fabric being seamed in the machine.

4. Feeding mechanism for sewing machines comprising a presser bar confined to axial movement above the work support of the sewing machine; a feed wheel rotatable about an axis carried by the presser bar for vertical movement directly with said bar; means for rotating the wheel to progress fabric along the work support relative to the stitch-forming instrumentalities of the machine; a presser foot in the line of feed ahead of the wheel; a horizontal link member pivoted at one end to the presser bar and having the presser foot pivotally connected thereto at the other end whereby said presser foot is accorded the capacity to move up and down independently of the wheel and to pivot angularly as the fabric passes beneath it; and means for yieldingly maintaining the presser foot in engagement with the fabric.

5. Feeding mechanism for sewing machines comprising a presser bar confined to axial movement above the work support of the machine; a bearing yoke secured in fixed relation to the bottom of the presser bar for vertical movement directly with said bar; a feed wheel journaled in said yoke; means for rotating the wheel to progress fabric along the work support relative to the stitch-forming instrumentalities of the machine; a presser foot adjacent the feed wheel; a horizontal link fulcrumed at one end to the yoke and at the other end affording pivotal connection for the presser foot so that the latter is accorded the capacity for up and down movement bodily as well as independent angular pivotal movement incident to the passage of the fabric therebeneath; and a finger spring on the yoke serving to maintain the presser foot in yielding engagement with the fabric.

45. 6. Feed mechanism for sewing machines comprising a presser bar confined to axial movement above the work support of the sewing machine; a bearing yoke secured in fixed relation to the bottom of the presser bar for vertical movement with said bar; a feed wheel journaled in said yoke; means for rotating the wheel to progress fabric along the work support relative to the stitch-forming instrumentalities of the machine; a presser foot adjacent the feed wheel; a horizontal link fulcrumed at one end to the yoke aforesaid and at the other end affording pivotal connection for the presser foot so that the latter is accorded the capacity for bodily up and down movement as well as independent angular pivotal movement incident to the passage of the fabric therebeneath; and a finger spring on the yoke with its free end bearing downwardly upon the link member to yieldingly maintain the presser foot in engagement with the fabric.

65. 7. Feed mechanism for sewing machines comprising a presser bar confined to axial movement above the work support of the sewing machine; a yoke at the bottom of the presser bar; a feed wheel journaled in said yoke; means for rotating the wheel to progress fabric along the work support relative to the stitch-forming instrumentalities of the machine; a presser foot adjacent the feed wheel; a horizontal link fulcrumed at one end to the yoke and at the other end affording pivotal connection for the presser foot so that the

latter is accorded the capacity for bodily up and down movement as well as independent angular pivotal movement incident to the passage of the fabric therebeneath; a finger spring on the yoke for maintaining the presser foot yieldingly in engagement with the fabric; and keeper means for limiting the downward movement of the presser foot relative to the feed wheel when the presser bar is actuated to lift said wheel clear of the work support.

8. Feed mechanism for sewing machines comprising a presser bar confined to axial movement above the work support of the sewing machine; a yoke at the bottom of the presser bar, said yoke having a projection; a feed wheel journaled in said yoke; means for rotating the wheel to progress fabric along the work support relative to the stitch-forming instrumentalities of the machine; a presser foot adjacent the feed wheel; a horizontal link fulcrumed at one end to the yoke and at the other end affording pivotal connection for the presser foot so that the latter is accorded capacity for bodily up and down movement as well as independent angular pivotal movement incident to the passage of the fabric therebeneath; a finger spring on the yoke with its free end bearing downwardly upon the link member to yieldingly maintain the presser foot in engagement with the fabric; and a slotted vertical keeper link connected to the link member aforesaid and adapted to cooperate with the projection on the yoke to limit the downward movement of said link member when the presser bar is elevated to lift the wheel clear of the work support.

9. Feed mechanism for sewing machines comprising a presser bar confined to axial movement above the work support of the sewing machine; a feed wheel journaled at the bottom end of the presser bar and adapted to react upon the work support in feeding fabric on the latter; clutch means within the feed wheel; a presser also connected to the presser bar with capacity to move upwardly independently of the wheel; and means for actuating the clutch means to intermittently rotate the wheel and thereby effect intermittent advance of fabric by the latter on the work support relative to the stitch-forming instrumentalities of the machine.

10. Feed mechanism for sewing machines having a needle arm above a work support, comprising a presser bar confined to axial movement in said arm; a feed wheel journaled at the lower end of the presser bar; a clutch incorporated with the wheel and having an actuating arm; and means for swinging the arm to effect intermittent advance of fabric by the wheel on the work support relative to the stitch-forming instrumentalities of the machine, including a rock shaft journaled on the needle arm aforesaid, an arm on the rock shaft, and linkage connections between the last mentioned arm and the clutch-actuating arm.

11. Feed mechanism for sewing machines having a needle arm above a work support, comprising a presser bar confined to axial movement in said arm; a feed wheel journaled at the lower end of the presser bar; a clutch incorporated with the wheel and having an actuating arm; means for swinging the arm to effect intermittent advance of the fabric by the wheel on the work support relative to the stitch-forming instrumentalities of the machine, including a rock shaft journaled on the needle arm aforesaid, an arm on the rock shaft, linkage connections between the

last mentioned arm and the clutch-actuating arm, and means whereby the movement imparted to the wheel at each actuation can be adjusted.

5 12. The combination in a sewing machine having a work support with an overhanging needle arm, and a longitudinal drive shaft beneath the work support, of feeding mechanism comprising a presser bar confined to axial movement in the 10 needle arm; a feed wheel carried at the bottom of the presser bar; clutch means associated with the wheel; and means for actuating the clutch means to intermittently rotate the feed wheel and thereby effect advancement of fabric on the work support relative to the stitch-forming instrumentalities of the machine, including a rock shaft journaled longitudinally of the needle arm, operating connections between the drive shaft and the rock shaft, and linkage connections between 15 20 said rock shaft and the clutch means.

13. The combination in a sewing machine having a work support, a feed dog beneath said work support, and a presser bar confined to axial movement above the work support, of auxiliary 25 feeding mechanism comprising a feed wheel jour-

naled on an axis at the bottom of the presser bar in the line of feeding rearward of the feed dog for vertical movement directly with said bar; an associated presser foot cooperating with the feed dog above the work support; and a link having 5 one end pivotally connected to the presser bar and affording at its other end a pivotal connection for the presser foot whereby the latter is accorded capacity for up and down movement relative to the feed wheel as well as independent 10 angular pivotal movement.

14. Feed mechanism for sewing machines having a needle arm above the work support, comprising a presser bar confined to endwise movement in said arm; a feed wheel at the lower end 15 of the presser bar; a rock shaft journaled on the overhanging arm; and means extending from said rock shaft to the wheel; means at the wheel operated by the first mentioned means for converting the oscillatory movements of the rock 20 shaft into intermittent rotary feed movements of said wheel for progression of the fabric on the work support relative to the stitch forming elements of the machine.
